ATTORNEY

UNITED STATES PATENT OFFICE

EDWARD C. KLAIBER, OF MEMPHIS, TENNESSEE, ASSIGNOR TO NATIONAL WASH-
BOARD COMPANY, OF CHICAGO, ILLINOIS, A CORPORATION OF WEST VIRGINIA

WASHBOARD

Application filed June 21, 1929. Serial No. 372,722.

This invention relates to wash-boards and pertains more particularly to a new and useful arrangement of that part of the wash-board above the rubbing surface, usually 5 designated the soap pan.

The class of wash-boards to which this improvement is especially well adapted is what is known as utility wash-boards, being small boards for use in pails, wash bowls and small 10 tubs.

The objects of the invention are to reduce the cost of manufacture, avoid likelihood of tearing the goods being rubbed and to provide in a unitary piece an intermediate cross 15 bar, a top bar and a soap pan, thereby doing away with the necessity of separately manufacturing these items and assembling them in a wash-board.

A further advantage of this unitary structure of the two cross bars and the soap pan is that leakage of water through or around the soap pan is avoided.

With the foregoing and certain other objects in view, which will appear later in the 25 specification, my invention comprises the devices described and claimed and the equivalents thereof.

In the drawings Fig. 1 is a front perspective view of a wash-board embodying my improvement.

Fig. 2 is a vertical section taken on line 2-2 of Fig. 1.

Fig. 3 is a perspective detail showing the 30 integral soap pan and cross bars.

Fig. 4 is an end view of the side rail shown in Fig. 2.

As is clearly shown in the drawings, a wash-board embodying my improvement 40 comprises a pair of spaced parallel side rails 1, 1 having longitudinal rabbets 2, 2 in the inner opposite surfaces thereof. A rubbing plate 3 of usual construction is mounted between the side rails, its edges received in the rabbets. The rubbing surface plate, as is 45 customary in wash-boards of this kind, is backed by a wooden panel 5 whose lateral marginal edges are likewise received in the rabbets, as shown in Fig. 2.

In applying my improved soap pan structure to a wash-board made up as above de-

scribed a board 4 of suitable width and length, whose thickness is equal to the width of the rabbet is shaped on one face to present a depressed channel 6 that constitutes the soap pan, leaving top and bottom marginal ribs or raised strips that constitute the respective top cross bar 7 and the intermediate cross bar or soap rest 8. Such a board, cut to proper length as indicated in Fig. 3, is inserted in the rabbets 2, 2 as in Figs. 1 and 2. 55

The upper edge 3^a of the corrugated rubbing plate 3 abuts against the lower edge of the soap rest 8, being concealed and protected by it so that articles being rubbed can not catch on the said edge 3^a. With that arrangement it is feasible to omit the customary groove in the lower edge of soap rest 8 to receive the edge of the rubbing plate. The back face of the board 4 is flush with the back face of the panel 5, since they both are snugly seated in the same rabbet 2. 60

Leakage, resulting from shrinkage, and seam-opening heretofore a common source of trouble in built-up wooden soap pans, is avoided in my structure. Obviously the soap board or pan can not part from its upper or lower cross bars 7 and 8 to produce a crack, which heretofore has been a frequent source of trouble in wash-boards having the soap channel or pan 6 and the top bar and soap rest 75 made in separate pieces. 80

With the construction herein shown it is merely necessary to provide a suitably rabbeted board, Fig. 3, of any suitable length, it being simply cut to the right length and inserted between the rails 1, 1, to provide a complete soap pan, top bar and soap rest assembly. 85

A saving of labor and material by manufacturing these parts in one piece is effected and considerable time is saved in assembling. 90

Having thus described my invention, what I claim and desire to secure by Letters Patent is:

In combination, a pair of spaced side rails longitudinally rabbeted along their inner faces, a rubbing board whose ends are received in said rabbets, a soap pan whose ends are likewise received in said rabbets, the middle part of one of the faces of said soap pan 95 100

shaped to present a thinned panel and to present along its top and bottom edges respectively, a top bar and an intermediate soap-support bar, the thickness of said bars being substantially equal to the width of said rabbits, for the purposes set forth.

In testimony whereof, I affix my signature.

EDWARD C. KLAIBER.
